UNITED STATES PATENT OFFICE.

CHARLES S. SHALLENBERGER, OF ST. LOUIS, MISSOURI, ASSIGNOR TO DOUBLE BODY BOLSTER COMPANY, A CORPORATION OF NEW JERSEY.

CAR END UNDERFRAME.

1,076,243.

Specification of Letters Patent.

Patented Oct. 21, 1913.

Application filed September 2, 1911. Serial No. 647,350.

To all whom it may concern:

Be it known that I, CHARLES S. SHALLENBERGER, a citizen of the United States, residing at St. Louis, Missouri, have invented a certain new and useful Improvement in Car End Underframes, of which the following is a full, clear, and exact description, such as will enable others skilled in the art to which it appertains to make and use the same, reference being had to the accompanying drawings, forming part of this specification, in which—

Figure 1 is a plan view of a car end under frame of my improved construction. Fig. 2 is a section taken lengthwise through the center of the car end under frame and upon the line 2—2 of Fig. 1. Fig. 3 is an enlarged detail section taken approximately on the line 3—3 of Fig. 2. Fig. 4 is a plan view 20 of a modified form of my improved car end underframe. Fig. 5 is a rear end elevation of the modified construction of the underframe, illustrated in Fig. 4.

This invention relates generally to car under frame construction and more particularly to an under frame of the ends of passenger cars having vestibule ends.

In Patent No. 873,800 issued to me December 17, 1907 I disclosed an under frame construction particularly adapted for use in connection with freight cars and my present invention is an improvement on the construction shown and described in said patent, and contemplates the combination of a series of special castings arranged and combined to form a comparatively light, strong and rigid under frame particularly adapted for use beneath the ends of passenger car bodies.

The principal objects of my invention are to provide a strong, rigid built-up car end under frame, the parts of which combine in resisting service strains and stresses, and which under frame can be easily assembled, or taken apart for the purposes of repair, and further to provide an under frame wherein the platform member carrying the buffing beam is supported from the end sill of the under frame member in cantilever

fashion, thereby taking the shearing strains off the rivets or like fastening devices used for attaching the platform member to the under frame member.

To the above purposes my invention consists in certain novel features of construction and arrangement of parts hereinafter more fully described and claimed.

As shown in the accompanying drawings the main casting of the under frame comprises a bolster 1, end sill 2, side sills 3, pair 60 of center sills 4 and diagonally disposed brace members 5, between the central portion of the bolster 1 and the ends of the end sill 2, all of which parts are formed integral.

The bolster 1 is preferably I-shaped in cross section having a center bearing plate 6 formed integral with its bottom flanges at its center, and provided at its ends with the pairs of depending perforated lugs 7 to 70 which the ends of the side truss rods are attached. The end sill 2 may be of any desired shape in cross section, and formed integral with the top of said end sill along the front edge thereof is a vertically disposed, upwardly projecting flange 8. The side sills 3, diagonally disposed brace members 5 and center sills 4 may be of any desired shape in cross section, and said center sills are spaced apart a sufficient distance to 80 receive the draft rigging.

The central portions of the center sills 4 are extended downward a short distance and formed in the inner faces of said downwardly extended central portions are longitudinally extending pockets or recesses 9 adapted to receive the ends of follower plates of the draft rigging carried by the under frame.

An integral transversely disposed plate 10 unites the upper portions of the center sills at a point preferably midway between the bolster 1 and end sill 2. The platform member of my improved under frame is preferably cast in one piece and comprises a horizontally disposed plate 11, vertically disposed front and rear walls 12 and 13, vertically disposed side walls 14 and centrally

disposed walls 15, which perform the function of braces.

The rear wall 13 is positioned directly against and is fixed to the central portion of 5 the vertically disposed flange 8 by means of rivets or like fastening devices. Formed integral with the under side of the plate 11 is a pair of longitudinally disposed vertical webs 16, portions of which project beneath 10 the top plate or flange of the end sill 2, and said projecting portions lie immediately against the inner faces of the vertically disposed webs of the center sills 4.

Supporting ribs or flanges 17 are formed 15 integral with the inner faces and lower edges of the center sills 4, which flanges or ribs extend beneath the webs 16 to support the same, and to take the shearing strain off the rivets or like fastening devices utilized 20 for fastening the projecting portion of the webs 16 to the center sills.

The sills of the car body (not shown) rest directly upon and are attached in any suitable manner to my improved car end 25 underframes, and when said sills are properly positioned their ends bear directly against the longitudinally disposed flange 8. Thus a very solid and substantial support is formed for the end portions of the car 30 body, and all buffing and pulling strains upon the buffing beam, and said underframes, are distributed over areas of considerable extent at both ends of the car body.

By my improved construction the plat- 35 form casting is supported from the end sill of the underframe casting in cantaliver fashion, and thereby the platform casting is capable of supporting great weight besides effectually resisting the various service 40 strains and stresses to which it is ordinarily subjected.

Formed integral with the underside of the platform casting, and at the front edge thereof is a transversely disposed plate 18 45 adapted to receive the stirrup or angle utilized for supporting the draw-bar. Formed integral with the lower edge of the front wall 12 of the platform casting is a forwardly projecting transversely disposed 50 plate 19, which serves as a support for the buffer beam 20. This buffer beam, which is preferably cast in a single piece, is hollow and is provided in its top surface with a centrally disposed recess 20 adapted to receive a threshold plate (not shown). This 55 buffering beam is rigidly fixed to the platform casting by means of rivets or like fastening devices inserted through suitable openings formed through the rear wall of said buffer beam, and through the front wall 12 of the 60 platform casting.

Formed through the front and rear walls of the buffer beam, and through the wall 12 of the platform casting are aligned openings

21 adapted to receive the stems of the buffer 65 plate, which is positioned in the usual manner immediately in front of the central portion of the buffer beam.

In the modified construction illustrated in Figs. 4 and 5 an extension 22 is formed integral with or fixed to the rear side of the bolster 1, and which extension is approximately of inverted U shape or box shape in cross section, and serves as a support and bearing for the attachment of the center 75 sills. By such construction the draft sills are in direct alinement with the center sills 4, and all direct buffing and pulling strains imparted to the underframes are, in turn, transmitted to the draft sills. 80

A car end underframe of my improved construction is composed of three main parts, which, when properly assembled and united, are so disposed with relation to one another as to act as a unit in effectually resisting all service strains and stresses, combined lightness of weight with great strength and rigidity, can be easily and cheaply manufactured, and assembled and the platform casting carrying the buffer beam is connected to and supported by the underframe casting after the manner of a cantaliver, thereby insuring great strength and carrying capacity of said platform casting and buffer beam. 90

It will be readily understood that minor 95 changes in the construction and combination of the various parts of my improved device may be made and substituted for those herein shown and described, without departing from the spirit of my invention, the scope 100 of which is set forth in the appended claims.

I claim:

1. In a car end underframe the combination with a cast metal structure comprising a bolster, an end sill and side sills, of a cast 105 metal platform rigidly fixed to the end sill and a separate cast metal buffer beam rigidly fixed to the platform casting.

2. The combination with a car end underframe casting, having an end sill, of a separate platform casting detachably connected to the end sill, webs on the platform casting, which webs extend beneath the end sill, and a separate buffer beam detachably connected to the platform casting. 110

3. The combination with a car end underframe casting, having an end sill, of a separate platform casting detachably connected to the end sill, webs on the platform casting, which webs extend beneath the end sill, 115 supports on the under frame for said webs, and a separate buffer beam detachably connected to the platform casting.

4. The combination with a car end underframe cast in a single piece, and having an 120 end sill and center sills, of a separate platform casting detachably connected to the end sill of the under frame, webs on the platform 125

casting, which webs extend beneath the end sill, and are attached to the center sills, and a separate buffer beam detachably connected to the platform casting.

5. 5. The combination with a car end underframe cast in a single piece, and having an end sill and center sills, of a separate platform casting detachably connected to the end sill of the underframe, webs on the platform casting, which webs extend beneath the end sill and are attached to the center sills, supports on the center sills for said webs, and a separate buffer beam detachably connected to the platform casting.
10. 6. The combination with a car end underframe having parallel center sills extending beneath its end sill, of a platform casting fixed to the end sill of the underframe, and a pair of webs integral with said platform casting, which webs extend beneath the end sill of the underframe and are fixed to the parallel center sills.

15. 7. The combination with a car end underframe casting having an end sill, of a separate platform casting detachably connected to the underframe casting, a flange on the forward end of the platform casting, and a separate buffer beam detachably connected to the front portion of said platform casting and supported by said flange.

20. 8. In a car end underframe the combination with a casting comprising a bolster, an end sill, side sills, center sills, diagonally disposed braces between the central portion of the bolster and the ends of the end sill, all of which parts are formed integral, of a separate platform casting detachably connected to the end sill, webs integral with said platform casting, which webs extend beneath the end sill and a separate buffer beam detachably connected to the platform casting.

25. 9. In car construction the combination with a car end underframe comprising a bolster, an end sill, a vertically disposed, longitudinally extending flange on said end sill, side sills, all of which parts are formed integral, of a separate platform casting detachably connected to the end sill and a separate buffer beam- detachably connected to the platform casting.

30. 10. In car construction the combination with a car end underframe comprising a bolster, an end sill, a vertically disposed, longitudinally extending flange on said end sill, side sills, center sills, all of which parts are formed integral, of a separate platform casting detachably connected to the end sill and a separate buffer beam detachably connected to the platform casting.

35. 11. In car construction the combination with a car underframe comprising a bolster, an end sill, a vertically disposed, longitudinally extending flange on said end sill, side

sills, center sills, diagonally disposed braces 65 between the central portion of the bolster and the end portions of the end sill, all of which parts are formed integral, of a separate platform casting detachably connected to the end sill and a separate buffer beam 70 detachably connected to the platform casting.

12. In car construction the combination with a car end underframe casting provided with a vertically disposed flange on the upper front edge of its end sill, and horizontally disposed flanges on its underside, of a separate platform casting detachably connected to the underframe casting, the rear end of which platform casting bears directly against the flange on the end sill portion of 80 the underframe casting and vertically disposed webs integral with and extending rearwardly from the platform casting, which webs rest upon the horizontally disposed flanges on the underside of the underframe casting.

13. In car construction the combination with a car end underframe casting provided with a vertically disposed flange on the upper front edge of its end sill, and horizontally disposed flanges on its underside, of a separate platform casting detachably connected to the underframe casting, the rear end of which platform casting bears directly against the flange on the end sill portion of 90 the underframe casting, vertically disposed webs integral with and extending rearwardly from the platform casting, which webs rest upon the horizontally disposed flanges on the underside of the underframe 100 casting, and a separate cast metal buffer beam detachably connected to the front end of the platform casting.

14. The combination with a car end underframe having an end sill and center sills, of a separate platform casting detachably connected to said end sill, webs on the platform casting, which webs extend beneath said end sill, and supporting means on the center sills of the underframe for said webs. 110

15. In a car underframe, a cast metal platform, vertically disposed, longitudinally extending webs on the underside of said platform, which webs extend rearwardly from the platform for engagement with the underframe of a car, and a buffer beam supporting flange on the front side of said platform casting.

16. In a car underframe, a cast metal platform, integral webs projecting rearwardly 120 from the underside of said platform for attachment to the underframe, and a horizontally disposed flange integral with and projecting outwardly from the front of the platform casting for engaging and supporting a buffer beam.

17. The combination with a car end underframe, of a platform casting detachably

connected to the end sill of the underframe, webs on the platform casting, which extend beneath the car end underframe and are connected thereto, supports on the car end underframe for said webs, and a separate buffer beam detachably connected to the platform casting.

In testimony whereof I hereunto affix my signature in the presence of two witnesses, this seventh day of August, 1911.

CHARLES S. SHALLENBERGER.
